[57] CLAIM

The ornamental design for a tire, as shown and described.

DESCRIPTION

FIG. 1 is a perspective view of a tire showing my new design, it being understood that the tread design is repeated uniformly throughout the circumference, the tire as shown schematically in solid lines and the opposite side is the same as that shown;

FIG. 2 is a front elevation view thereof; and

FIG. 3 is a side elevation view thereof.

FIG 1

FIG 2

FIG 3
